UNITED STATES PATENT OFFICE

104,751

DESIGN FOR AN EMBROIDERED NET

Max Sokoloff, Woodmere, N. Y.

Application April 19, 1937, Serial No. 68,873

Term of patent 3½ years

To all whom it may concern:

Be it known that I, Max Sokoloff, a citizen of the United States, residing at Woodmere, in the county of Nassau and State of New York, have invented a new, original, and ornamental Design for Embroidered Net, of which the following is a specification, reference being had to the accompanying drawing, forming part thereof, wherein—

The figure is a plan view of embroidered net showing my new design, with the design unit indicated in dot and dash lines.

I claim:

The ornamental design for an embroidered net substantially as shown and described.

MAX SOKOLOFF.
